Des. 223,786
Patented June 6, 1972

223,786

TAPE AND BANDAGE CUTTER

Cecil E. Phillips and Fay M. Bennett, Eugene, Oreg.,
assignors to Saf-Pla Corporation, Eugene, Oreg.

Filed Dec. 31, 1970, Ser. No. 26,717

Term of patent 14 years

Int. Cl. D24—05
U.S. Cl. D83—12

FIG. 1

FIG. 2

FIG. 3

FIG. 4

FIG. 5

FIG. 6

FIG. 1 is an elevational view of one side of our tape and bandage cutter, showing our new design.

FIG. 2 is an elevational view of the other side of our tape and bandage cutter.

FIG. 3 is a top plan view of our tape and bandage cutter.

FIG. 4 is a bottom plan view of our tape and bandage cutter.

FIG. 5 is an end view of the left end of the cutter as illustrated in FIG. 1.

FIG. 6 is an end view of the right end of the cutter as illustrated in FIG. 1.

We claim:

The ornamental design for a tape and bandage cutter, as shown.
